Warren G. Ogden

UNITED STATES PATENT OFFICE.

FRANCIS A. BRAGG, OF FOXBORO, MASSACHUSETTS.

CHOKE CONTROLLER.

Application filed February 13, 1925. Serial No. 9,025.

To all whom it may concern:

Be it known that I, FRANCIS A. BRAGG, a citizen of the United States, residing at Foxboro, in the county of Norfolk and State of Massachusetts, have invented certain new and useful Improvements in Choke Controllers, of which the following is a specification.

The present invention relates to internal combustion engines, and more particularly to choke controls therefor which are used principally in connection with the carbureters of automobiles to provide a temporary rich mixture to facilitate starting a cold motor. Specifically the present invention relates to choke controls for Ford motors.

In starting a cold Ford motor the choke rod is pulled out at the instrument board and held out, because of the spring return, to provide the carbureter with a rich mixture until the motor becomes warm enough to operate with the lean mixture which the carbureter is adjusted to provide under normal operating conditions. In winter weather when the cold varies in intensity from day to day it is highly desirable to operate the carbureter with a mixture which varies in richness inversely with the fall in temperature. To do this at the present time would require continuous tampering with the carbureter adjustment which is impracticable.

The object of the present invention is to produce a choke control which, in addition to providing the carbureter with an operating mixture which is leaner than the starting mixture but richer than the mixture which the carbureter is adjusted to provide.

To the accomplishment of this object, and such others as may hereinafter appear, the features of the invention relate to certain devices, combinations, and arrangements of parts, hereinafter described and then set forth broadly and in detail in the appended claims which possess advantages readily apparent to those skilled in the art.

The various features of the present invention will be best understood from an inspection of the accompanying drawings illustrating the best form of the invention at present devised, in which,

Figure 1 is a right side elevation of the choke control, the dash, cowl and instrument board being shown in section, and

Fig. 2 is an enlarged detail in right side elevation showing an exaggerated arrange-

ment of the adjusting screw with relation to the choke rod and instrument board.

Referring to the drawing the carbureter 3 has a pipe connection 4 which is controlled by a choke valve (not shown) having fixed thereto an operating arm 5. The choke valve is normally held in a non-choking position by a coiled spring 6, having a fixed anchorage 7. The arm 5 is operated against the tension of the spring 6 by a rod 8 from one arm of a bell crank lever 9 pivoted on a bracket 10 carried by the dash 11. The other arm of the bell crank lever 9 is engaged by a choke rod 12 extending diagonally upward through the instrument board 13 terminating on the cab side of the board. The choke rod 12 is provided with a head or button 14 at its free end constituting a hand piece by which the choke rod may be pulled to move the choke valve into choking position against the tension of the spring 6.

With this construction, which is the usual equipment of a Ford motor, the choke rod occupies either a normal inactive position in which the choke valve is open to permit a free flow of air in the pipe 4 or a temporary starting position in which the choke valve is closed or partially closed to choke the air in the pipe 4 and thus provide the carbureter with a rich mixture to facilitate starting a cold motor.

In order to provide an intermediate operating position for the choke rod in which the choke valve is slightly closed to provide the carbureter with a mixture leaner than the starting mixture but richer than the mixture for which the carbureter is adjusted the button 14 is tapped to receive the threads of a screw 15. One end of the screw 15 is provided with a knurled head 16 by which the screw may be adjusted relatively to the button 14. The other end of the screw 15 is arranged to engage the instrument board 11 and thus act as a stop to prevent the return of the choke rod from its temporary starting position to its normal inactive position when the operator, after the motor is warmed up, releases the choke rod to the influence of the spring 6. The screw 15 is locked in any desired position of adjustment by a set nut 17 mounted on the screw 15 and arranged to engage the button 14.

With this construction, after the choke control has been pulled out to provide a rich starting mixture it can be dropped back

instantly to the position determined by the stop screw 15. By backing off the nut 17 and rotating the screw 15 within the button 14 and resetting the set nut 17 very fine adjustments can be secured to obtain an operating mixture to suit any atmospheric condition. If, after operating the motor with the choke rod in its intermediate operating position, it should be desired to operate with the lean mixture which the carburetor is adjusted to provide the screw 15 may be withdrawn from the instrument board by backing it off within the button 14 thus restoring the choke rod to the influence of the spring 6 (Fig. 1).

It will be apparent to those skilled in the art that the features of my invention may be incorporated in a Ford motor car in an exceedingly simple manner. As the only change required is in the button 14 which projects beyond the cab side of the instrument board no work of any kind is required on the instrument board. The change from the old to the new control may be made without the assistance of a skilled mechanic. All that is required is to disconnect the usual choke rod from the bell crank lever 9 and substitute a new choke rod having the screw 15 threaded through the button 14 together with the set nut 17. The old choke rod may then be used in another car after it is provided with a stop screw 15 and a set nut 17, which is an easy and cheap operation.

The nature and scope of the invention having been indicated, and its preferred embodiment having been specifically described, what is claimed as new, is:—

1. A choke control having, in combination, a choke rod extending through an instrument board having a normal inactive position and movable by the operator into a temporary starting position, and means mounted entirely on that portion of the choke rod that extends beyond the cab side of the instrument board for preventing the choke rod from returning to its normal inactive position when released by the operator.

2. A choke control having, in combination, a choke rod having a normal inactive position and a temporary starting position, and means mounted upon and movable relatively to and longitudinally of the choke rod for determining an intermediate operating position.

3. A choke control having, in combination, a choke rod having a normal inactive position, a temporary starting position and an intermediate operating position, and a screw carried by the choke rod for determining its intermediate operating position.

4. A choke control having, in combination, an instrument board, a choke rod having a normal inactive position and movable

by the operator into a temporary starting position, and a screw interposed between the choke rod and the instrument board for preventing the choke rod returning from its temporary starting position to its normal inactive position when released by the operator.

5. A choke control having, in combination, a choke rod having a normal inactive position and a temporary starting position, and an adjustable stop member for determining an intermediate operating position, said stop and choke rod being relatively adjustable from the cab side of the instrument board to vary said intermediate position at the will of the operator.

6. A choke control having, in combination, an instrument board, a choke rod having an operating button thereon, said choke rod having a normal inactive position, a temporary starting position, and an intermediate operating position, and a screw rotatably mounted on said button and arranged to engage the instrument board for determining the intermediate operating position of the choke rod.

7. A choke control having, in combination, an instrument board, a choke rod having an operating button thereon, said choke rod having a normal inactive position, a temporary starting position, and an intermediate operating position, a screw threaded through said button and adjustable to engage the instrument board for determining the intermediate operating position of the choke rod, and a set nut carried by the screw and arranged to engage the button for locking the screw in any desired position of adjustment.

8. A choke control comprising a choke rod adapted to be connected to the operating mechanism of the choke valve of a carburetor, and an adjustable stop member carried by its end under control of the operator and mounted for movement relatively to and longitudinally of the rod.

9. A choke control comprising a choke rod adapted to be connected to the operating mechanism of the choke valve of a carburetor, an adjustable stop member carried by its end under control of the operator and mounted for movement relatively to and longitudinally of the rod, and means for retaining said stop member in any desired position of adjustment.

10. A choke control comprising a choke rod adapted to be connected to the operating mechanism of the choke valve of a carburetor, having an operating button, said button having a hole the axis of which is substantially parallel to the axis of the rod, and a stop member adjustably seated in said hole and movable therethrough to different positions relative to the end of the rod.

FRANCIS A. BRAGG.
